UNITED STATES PATENT OFFICE.

FREDERICK C. JONES, OF CAMDEN, NEW JERSEY, ASSIGNOR TO VICTOR TALKING MACHINE COMPANY, A CORPORATION OF NEW JERSEY.

RECORD HOLDER FOR TALKING MACHINES.

Application filed December 1, 1923. Serial No. 677,947.

To all whom it may concern:

Be it known that I, FREDERICK C. JONES, a citizen of the United States, and a resident of Camden, in the county of Camden, State of New Jersey, have invented certain new and useful Improvements in Record Holders for Talking Machines, of which the following is a specification.

My invention relates to record holders for talking machines and in particular relates to the providing of record holding and retaining devices within the casing of relatively small portable cabined talking machines when the machine is being carried from one place to another.

In designing and constructing portable cabined or enclosed talking machines, several factors at least have to be considered. The motor for turning the turntable must be large enough to run steadily and sufficiently long to reproduce one or more records without rewinding; the horn or amplifier must be large enough to reproduce sound in volume fairly comparable to that obtainable from large non-portable machines; and the size of the cabinet must be as small as it can be made with the factors above noted taken into consideration.

Hence it is that the various parts of the sound reproducing mechanism for a portable talking machine are arranged and disposed in the casing or cabinet in the most compact and advantageous manner, it being desirable to make the cabinet itself only large enough to contain the said mechanism with the result that almost all of the space within the cabinet is occupied by the sound reproducing mechanism.

Of course, it would be possible to increase the size of the casing of a portable talking machine to provide a compartment in which records might be placed and transported, but that is undesirable because portable talking machines are at best quite heavy and bulky and any increase in the size of the cabinet would detract from the portability of the machine.

In almost any portable talking machines, and particularly in those of the type where in the sound reproducer is connected to the free end of a horizontally swinging pivot ed tone arm to be propelled across the record by the engagement of the stylus with the sound record groove, there must be a clear

space between the turntable and the lower surface of the swinging arm because the axis of the swinging portion of the tone arm and the axis of the circular sound box attached thereto are in substantially the same plane and the distance between the axis of the sound box and the turntable is consequently considerably greater than the radius of the largest transverse section of the horizontally swinging portion of the tone arm. This clear unoccupied space between the turntable and the swinging arm is horizontally as large or larger than the turntable and the record adapted to be placed thereon, and said space is vertically as high as a stack of five or six or possibly more disc talking machine records. It is this space that I utilize to store a plurality of records and fixedly clamp them in said space when the machine is being transported from place to place without increasing in any manner whatsoever the outside dimensions of the casing or cabinet, and this constitutes one of the objects of my invention.

In some talking machines of the type above referred to the swinging tone arm may be swung laterally when the machine is not being operated to reproduce sound, so that no part thereof is vertically over the turntable. In such machines there may be even more space vertically above the face of the turntable on which records may be stored during the transporting of the device. In such constructions the height of the stack of records which may be so placed on the turntable would not be necessarily limited to the distance between the turntable and the underside of the tone arm but by the shortest distance between the interior of the lid and the surface of the turntable.

A further object of my invention is to hold a plurality of records securely and immovable with respect to each other in a space of a cabinet of a portable talking machine which might be otherwise empty during transportation of the machine.

A further object of my invention is to provide means for holding a stack of records on the turntable of a portable talking machine in such a way that they cannot move or chafe during transportation of the machine.

A further object of my invention is to provide a construction in which with equal

facility one or a plurality of records may be securely held and clamped on the turntable by merely closing and locking or fastening the pivoted lid of a portable talking machine.

A further object of my invention is to provide means operative to automatically clamp and hold on a turntable one or a plurality of talking machine records by merely closing the lid and fastening it in closed position.

Further objects of my invention will appear in the specification below.

Referring to the drawings forming a part of this specification and in which the same reference characters are used throughout the various views to designate the same parts,

Fig. 1 is a longitudinal view in section of the upper portion of a cabinet of a portable talking machine and the pivoted lid or cover thereof, showing in dotted lines the relative position and size of the tapering swinging tone arm and sound box; the turntable with a plurality of disc talking machine records stacked and clamped thereon, and the record clamping member secured to the inside of the lid or cover of the cabinet or casing in alinement with the turntable spindle;

Fig. 2 is a vertical sectional view on a scale larger than that of Fig. 1 of the clamping and holding member and of portions of a plurality or stack of talking machine records supported on the turntable with the upper end or extension of the spindle passing through the usual holes at the centers of the records; and

Fig. 3 is a sectional view on the line 3—3 of Fig. 2.

Referring first to Fig. 1, the cabinet, box or casing 1 (of which the top edge only is shown) of a portable cabinetized talking machine is provided with a lid 2 pivoted or hinged to the rear wall 3 of the casing 1 on hinges 4. The tone arm 5 is mounted in the cabinet to swing relatively horizontally on a pivotal mounting 6 which may be located or mounted in the mouth or larger end 7 of the amplifier 8.

The motor board 9 is mounted on and is secured within the upper end of the cabinet or casing 1 in any suitable manner, and to the underside of the motor board 9 is attached by screws 10, 10, the motor frame 11 which carries the motor mechanism (not shown) for driving the spindle 12 which extends vertically through a hole 13 in the motor board 9. On the spindle 12 is mounted a turntable 14, the hub 15 of which is formed with a hole or bore which fits the outer surface of the turntable spindle 12. The lower end of the hub may be provided with a notch 16 into which fits a pin 17 extending transversely through said spindle, to

prevent any relative rotational movement between the turntable and the spindle.

In talking machines, as usually constructed, the turntable spindle extends only a short distance above the top surface of a record placed on the turntable, its function being for positioning the record concentrically with respect to the turntable. The upper end of the turntable spindle is usually integral with the spindle.

But in transporting a portable talking machine, the box or casing is liable to be put in any position. In fact, the handles of such machines are usually so arranged on a side wall of the box or casing that the spindle is horizontal when the machine is being carried from place to place. It is therefore desirable to secure the turntable to the spindle in such a manner that it will not become separated from the spindle during the transportation of the machine and handling thereof.

I make the turntable spindle in two parts, viz, the main portion 12 around the top of which the turntable hub 15 smoothly fits and a coaxial extension 18 which projects above the upper surface of the turntable 14 a little higher than the height of a stack of as many records as can be placed on the turntable without interfering with the tone arm or the closing of the lid 2.

The extension 18 of the spindle is so constructed that in addition to performing its function of positioning a stack of records concentrically with the center of the turntable, it also performs the function of inseparably holding the turntable on the spindle. To this end the upper end of the main portion of the spindle 12 is provided with a screw-threaded hole 19 adapted to receive the correspondingly threaded end 20 of the extension 18 of the spindle. This extension 18 is provided with a flange 21 which is greater in diameter than the diameter of the top of the main portion of the spindle, and when connected to the spindle, as shown in Fig. 1, it provides a shoulder which prevents the turntable from being separated from the spindle. The free end of the extension 18 may be provided with a transverse hole 22 in which a rod may be inserted for tightly securing the extension 18 to the upper end of the main portion of the spindle 12.

On the inside of the lid or cover 2 of the cabinet and in alinement with the spindle 12 when the lid is closed, is secured a clamping device 23 comprising a base plate 24 adapted to be secured by screws 25 to the lining or sound deflector 26, and preferably to a block or strip 27 of wood secured to the lid between the inside of the outer portion of lid and the lining 26. The base plate is provided with a shallow cup-like projection or cylinder head 28 which may be perma-

nently secured to the base plate 24 by upsetting the end of a rivet-like lug 29 passing through a suitable hole in the base plate 24. The outer surface of this projection 28 may 5 be screw-threaded to fit corresponding screw-threads in the inside surface of one end of a cylindrical casing 30. The opposite end of the cylindrical casing 30 is provided with a circular opening 31 through which a 10 plunger 32 is adapted to freely pass. The diameter of the opening 31 is somewhat less than the diameter of the bore through the cylindrical casing 30 so that the lower end of the cylindrical casing 30 is provided with 15 a shoulder 33. The plunger 32 is provided on its inner end with a circular flange 34 adapted to smoothly fit and slide against the inner cylindrical surface of the casing 30 and its outer end may be of slightly smaller 20 diameter than the outside diameter of the plunger proper and may be provided with screw-threads 35 adapted to fit into a correspondingly threaded hole at the center of 25 a disc 36 to form a circular head 37 on the free end of the plunger 32. The lower face 30 of this head 37 is preferably provided with a washer 38 of felt or other soft yielding material secured thereto in any suitable manner, as by gluing or cementing the felt to the face of the disc 36. In the passage 35 through the plunger 32 is provided a ledge or shoulder 40 upon which is seated a ring or washer 41 and between this ring 41 and the cupped projection 28 is compressed 40 a spiral spring 42 which exerts a pressure against the plunger tending to force the plunger and the parts carried thereby outwardly away from the base plate 24.

In Fig. 1 the relative position and size of 45 the tone arm 5 and sound box 43 when the latter is resting on the turntable 14 and the lid is raised, is indicated in dotted lines. The diameter of the sound box 43 is considerably larger than the diameter of the 50 horizontally extending portion of the tapered arm or tone arm 5 but the axis of the sound box and the axis of the horizontally extending tone arm lie in substantially the same plane 44. The underside of the tone arm 5 is therefore substantially spaced from the top surface of the turntable and when the sound box 43 is removed from the end 55 of the tone arm and the tone arm is swung laterally to one side of the casing, as many records may be stacked on the turntable with the extension 18 passing through the usual holes in the centers of the records as will occupy the space between the underside of the tone arm 5 and the surface of the turntable. If the machine is wide enough to 60 permit the tone arm 5 to be swung laterally so that no part of it is over the turntable, then even more records may be stacked on the turntable so long as the top record does 65 not engage the lid 2 or the lining or deflector

26 inside of the lid or cause the plunger to strike against the bottom of the cylinder before the lid is closed.

The operation of the device is as follows:

Assuming the lid 2 to be raised, the sound 70 box 43 to have been removed from the tone arm 5, or swung therewith to one side and fastened or secured there in any suitable manner, any suitable number of talking machine records are placed on the turntable, the upper extension of the spindle passing through the usual holes in the centers of the records. The lid 2 is now slowly lowered about the pivot formed by the 75 hinges 4. As soon as the head 37 engages the top record of the stack 45 of records, its downward movement with the cover or lid 2 stops as the lowering of the lid or cover continues, the outer cylindrical casing 30 slides downwardly over the plunger 32 80 compressing the spring 42, and this continues until the edges of the lid rest on the top edges of the casing and the lid is closed. This final position is shown in Figs. 1 and 2. The lid is then fastened or locked as by the 85 fastenings 46.

In Figs. 1 and 2, six records are shown in the stack 45. If a fewer number of records are placed on the turntable, the hole or passage 39 through the plunger 32 and through 90 the washer 38 and through the spring 35 all being larger than the outside diameter of the extension 18 of the spindle 12 will permit the plunger to pass downwardly over the spindle until the head 37 engages the 95 topmost record, whereupon the downward movement of the plunger with the lid or cover will be arrested and the cylinder 30 will slide over the plunger 32 until the lid 100 is closed.

Since the operation of the clamping device 23 takes place during the last one or two inches of the movement of the front edge of the cover or lid 2 and since the 105 hinges 4 are relatively remote from the plunger, the arc through which the clamping device moves after the plunger engages the topmost record is exceedingly slight. It is substantially a straight line and any 110 outward slide or slip of the head 37 on the 115 face of the record is so slight as to be negligible.

To put the machine into sound reproducing condition, it is only necessary to unlock the fastenings 46 and raise the lid 2 whereupon the reverse of the above described operation takes place. The cylinder 30 rises with the lid until the shoulder 33 engages the flange 34 on the plunger 32 whereupon the cylinder and plunger move 120 as one with the cover away from the stack of records. The lid may be held open by any well-known lid supporting device.

The stack of records is now removed from the turntable, the arm is swung over the 125 130

turntable; and the sound box is re-attached to the arm or swung on it to reproducing position, whereupon the machine is ready to reproduce sound from any record which may be placed upon the turntable.

My device comprises a spring pressed plunger carried by the lid operative to automatically clamp one or more records with the spindle passing through the central 10 holes thereof, by and between it and the turntable, by merely lowering the hinged lid to close the cabinet or casing and then fastening or locking the lid in closed position.

15 The travel of the plunger is preferably such that the head 37 will engage the upper surface of the turntable when the lid is closed and no records are on the turntable. The opening or passage through the 20 plunger, washer and spring is large enough to permit the spindle to enter the same without contact with the device whether there be no records or one or more or the complement of records on the turntable 25 when the lid is closed.

I have also provided an arrangement and construction whereby a limited number of records, namely, from one to six or possibly more depending upon the thickness 30 of the individual records, may be conveniently stored for transportation within a portable talking machine, without increasing in any manner the size of the cabinet, and such limited number of records, 35 particularly if they have recorded selections on both sides, is generally sufficient to meet the requirements of many occasions.

Having thus described my invention, I claim:

40 1. The combination with a portable talking machine comprising a casing, a turntable and a lid for said casing, of a spindle extending upwardly from said turntable a distance equal to the thickness of several 45 disc records, and means secured to the inside of the lid to hold a stack of disc records on said turntable and spindle when said lid is closed.

2. The combination with a portable talking machine comprising a casing, a turntable, a spindle extending upwardly from said turntable, and a lid for said casing, of compressible means secured to the inside 50 of said lid to automatically clamp a stack of disc records on said spindle, by and between said turntable and said means, upon the closing of said lid.

3. The combination with a portable talking machine comprising a casing, a turntable and spindle extending upwardly from said turntable, and a lid for said casing, of means secured to said lid to automatically 60 clamp, by and between said turntable and said means, a limited number of records on said spindle upon the closing of said lid.

4. The combination with a portable talking machine comprising a casing, a turntable, a lid for said casing, and a tone arm adapted to swing horizontally over said turntable, of a spindle extending upwardly 70 to substantially the level of the underside of said tone arm, and compressible means secured to the inside of said lid to hold a limited number of records on said spindle clamped by and between said means and said turntable when said lid is closed.

5. The combination with a portable talking machine comprising a casing, a turntable, a spindle extending upwardly from 80 said turntable, and a lid hinged on one side of said casing, of means secured to the inside of said lid to clamp a number of records on said spindle between said turntable and said means, said means comprising a casing secured to said lid, a plunger mounted 85 and retained in said casing, and a spring tending to force said plunger outwardly from said casing.

6. The combination with a portable talking machine comprising a casing, a turntable, a spindle extending upwardly from 90 said turntable, and a lid hinged on one side of said casing, of means secured to the inside of said lid to clamp a number of records on said spindle between said turntable and said means, said means comprising a casing secured to said lid, a plunger mounted 95 and retained in said casing, and a spring tending to force said plunger outwardly from said casing, said plunger being 100 in alignment with said spindle when said lid is closed and providing an opening therein for the reception of the upper end of said spindle.

7. The combination with a portable talking machine comprising a casing, a turntable and a cover for said casing, of a spindle extending upwardly from said turntable a distance equal to the thickness of 110 several disc records, means secured to the inside of said cover to hold a stack of records on said turntable and spindle when said cover is closed, and means to retain said cover in closed position.

8. The combination with a portable talking machine comprising a casing, a turntable, a cover for said casing and a tone arm adapted to swing horizontally over said turntable, of a spindle extending upwardly 115 to substantially the level of the underside of said tone arm, compressible means secured to the inside of said cover to hold a limited number of records on said spindle clamped by and between said turntable and said means when said cover is closed, and means to retain said cover in closed position.

9. The combination with a portable talking machine comprising a casing, a turntable, a spindle extending upwardly from 120 125 said turntable, a cover for said casing and a tone arm adapted to swing horizontally over said turntable, of a spindle extending upwardly to substantially the level of the underside of said tone arm, compressible means secured to the inside of said cover to hold a limited number of records on said spindle clamped by and between said turntable and said means when said cover is closed, and means to retain said cover in closed position.

130

- 5 said turntable and a cover for said casing, of means secured to the inside of said cover to clamp a number of records on said spindle by and between said turntable and said means, said means comprising a casing secured to said cover, a plunger mounted and retained in said casing and a spring tending to force said plunger outwardly from said casing, and means to lock said 10 cover in closed position.
10. The combination with a portable talking machine comprising a casing, a turntable, a spindle extending upwardly from said turntable, a cover for said casing, and 15 means to fasten said cover in closed position, of means secured to the inside of said cover to clamp a number of records on said spindle by and between said turntable and said means, said means comprising a casing, a plunger mounted and retained in said 20 casing, and a spring tending to force said plunger outwardly from said casing, said plunger being in alinement with said spindle when said lid is closed and providing an opening therethrough for the reception of the upper end of said spindle. 25
11. In a record clamping device, the combination of a plate adapted to be secured to the inside of the lid of a talking machine, a cylinder mounted thereon, a plunger mounted to reciprocate in said cylinder and having an axial bore throughout its length providing a shoulder near the outer end of said bore of said plunger, a cylindrical spring mounted within said cylinder and said plunger, having its outer end seated on said shoulder and providing a clear passage through said plunger and the interior of said spring to substantially the bottom of said cylinder, and means to 30 limit the outward movement of said plunger. 35
- 15 In witness whereof, I have hereunto set my hand this 28th day of November, 1923.
- 20 FREDERICK C. JONES.

Certificate of Correction.

It is hereby certified that in Letters Patent No. 1,563,299, granted November 24, 1925, upon the application of Frederick C. Jones, of Camden, New Jersey, for an improvement in "Record Holders for Talking Machines," errors appear in the printed specification requiring correction as follows: Page 1, line 96, for the misspelled word "recurely" read *securely*; page 3, line 83, after the word "stops" insert the word *but*; and that the said Letters Patent should be read with these corrections therein that the same may conform to the record of the case in the Patent Office.

Signed and sealed this 19th day of January, A. D. 1926.

[SEAL.]

WM. A. KINNAN,
Acting Commissioner of Patents.
